UNITED STATES PATENT OFFICE.

CHARLES A. HOFFMAN, OF MINNEAPOLIS, MINNESOTA.

MACHINE FOR GRINDING MULTIFOCAL LENSES.

1,241,628.

Specification of Letters Patent.

Patented Oct. 2, 1917.

Application filed May 17, 1913. Serial No. 768,289.

To all whom it may concern:

Be it known that I, CHARLES A. HOFFMAN, a citizen of the United States, residing at Minneapolis, in the county of Hennepin and State of Minnesota, have invented certain new and useful Improvements in Machines for Grinding Multifocal Lenses; and I do hereby declare the following to be a full, clear, and exact description 10 of the invention, such as will enable others skilled in the art to which it appertains to make and use the same.

My invention has for its object to provide an improved lens grinding machine especially adapted for use in grinding bifocal or multifocal lenses, such as used in spectacles, eye glasses, and the like. Generally stated, the invention consists of the novel devices and combinations of devices herein- 20 after described and defined in the claims.

In the accompanying drawings which illustrate the invention, like character indicate like parts throughout the several views.

Referring to the drawings,

25 Figure 1 is a plan view with some parts broken away and with some parts removed, showing the improved machine;

Fig. 2 is a view partly in side elevation and partly in vertical section, and with 30 some parts broken away, showing the improved grinding machine;

Fig. 3 is a bottom plan view of the machine, some parts being broken away;

Fig. 4 is a side elevation showing the 35 lower portion of the machine;

Fig. 5 is a vertical section on the line x^5-x^6 on Fig. 2, some parts being removed;

Fig. 6 is a detail in section on the line x^6-x^6 on Fig. 1, some parts being broken 40 away; and

Fig. 7 is an enlarged section taken on the line x^7-x^7 on Fig. 5.

In the construction illustrated, the various parts of the machine are supported directly or indirectly on the framework 1 having a table 2 with bearing pedestals 3-4 and 5-6.

Pivotedly mounted on the upper ends of the pedestals 3-4, are short levers 7-8 50 provided at their rear ends with handle bar extensions 7^a and 8^a, respectively, that are capable of vertical movements in respect to the said levers. The front ends of the said levers 7-8 are connected by links 9 to wrist pins 10 carried by crank disks 11 secured 55 on the upper ends of upright countershafts

12 journaled in the pedestals 5-6 and extended downward through the table 2. To make the wrist pins 10 capable of variable throw, they are adjustably connected to the 60 crank disks 11, by clamping bolts 13, the heads of which work in undercut diametrical channels 14 formed in the face of the said disks. The bolts 13 are provided with clamping nuts 15 (see particularly Fig. 6), 65 by means of which, the said wrist pins 10 may be secured in their different adjustments.

In Fig. 5, a bifocal lens is indicated by the character y . The convex surface of this 70 lens is cemented, or otherwise temporarily secured to the concave upper face of the face plate 16 secured on the upper end of a spindle 17 journaled in a suitable bearing 18 on the table 2, and provided at its lower 75 end with a groove pulley 19 and hand wheel 20. The spindle 17 and face plate 16 are given a constant rotary motion, preferably from a small electric motor 21, through connections presently to be described. The 80 said motor 21 is shown as suitably secured to the underside of the table 2 and its armature shaft 21^a is journaled to suitable bearings on the frame 1, and is provided with groove pulleys 22, 23, 24 and 25. A belt 26 85 runs over the pulley 23 and over the pulley 19 on the said spindle 17.

Belts 27 run over the pulleys 22 and 25 and over groove pulleys 28 on the lower 90 ends of the crank disk shafts 12.

Journaled, as shown, in bearing brackets 29, on the lever handle bars 7^a and 8^a and capable of vertical movements therethrough are spindles 30, preferably constructed with enlarged lower ends 30^a having depending 95 spherical heads 31 and diametrically opposite pins 32. The spherical heads 31 are rigidly secured to the lower ends 30^a but the pins 32 are loose for vertical movements therein. Grinding tools in the form of 100 disks 33 are mounted for wobbling movements on the heads 31 and are provided with diametrically opposite perforations or indentations in which the ends of the co-operating pins 32 are seated. In this way, 105 the pins 32 act as driving pins to cause the disks 33 to rotate with the spindles 30 and at the same time, the said disks are permitted to wobble or oscillate to adapt themselves to the curve of the lens surface which 110 is being ground thereby. One of these grinding disks, to-wit, the disk shown at

the right in Fig. 5, is adapted to grind the distance surface of the lens while the other disk is adapted to grind the reading surface of the said lens. These disks, by oscillatory movements of the spindles 30, are caused to travel back and forth over the surface which they are intended to grind, and this movement may be very accurately regulated by proper adjustments of the 5 throws of the coöperating wrist pins 10 of the crank disks 11. The said crank disks are arranged to rotate in the same direction, so that the grinding disks will move simultaneously in the same direction rather than 10 toward and from each other, which latter movement would cause a conflict by engagement of the two grinding disks at extreme inward movements.

The grinding disks 33 are held or pressed 20 downward against the lens, partly by gravity and partly by the action of the coiled springs 34, which, as shown, are attached to the table 2 and to the outer ends of the lever handle bars 7.

25 The bearing brackets 29 in the lever handle bars 7^a and 8^a, are provided with recesses to receive grooved pulleys 35, through which the spindles 30 work vertically. The spindles 30 are provided with long key-ways 36 (see Fig. 5) that are engaged by key lugs 37 on the pulleys 35 (see Fig. 7).

Driving belts 38 run over the pulleys 35, over idle guide wheels 39 journaled to the sides of the levers 7—8, and under groove 35 pulleys 40 carried by a counter-shaft 41 journaled in suitable bearings on the frame 1. The counter shaft 41 is driven from the motor armature shaft 21^a, through a belt 42 which runs over the pulley 24 and over a. 40 pulley 43 on the said counter shaft. The table 2 is provided with segmental clearance passages 44 (see Figs. 1 and 2) through which the vertically extended portions of the driving belts 38 are arranged to pass.

45 When the machine above described is in action, it is evident that the face plate 16 and the lens 2 carried thereby, and both of the grinding disks which are operative on the lens, will be constantly rotated on their own axes, and at the same time, the said grinding disks will be oscillated so that the one will travel over the entire "distance" surface of the lens and the other will travel over the entire "reading" surface of the lens. The oscillatory or traveling movements of the two grinding disks should be 50 so nicely regulated that the one will travel just to, but not at all beyond the surface that is being ground or polished by the other

grinding disk. Also, it is of the greatest 60 importance to note that while the grinding actions of the two disks are independent, one of the other, they may be performed simultaneously without interference, one with the action of the other. It will also be remembered that oscillatory movement or travel of the two grinding disks may be independently regulated.

Fig. 5 shows the proper adjustment of the grinding spindles for grinding both the 70 near vision and the long vision zones of the lens. Fig. 1 does not, however, show such adjustments, but it is evident that such adjustment may be accomplished by proper setting of the crank links 9 in respect to 75 the crank disks 11.

What I claim is:

1. A machine for grinding multifocal lenses comprising two oscillatory spindle supports, rotary spindles carried by said supports and provided each with its own grinding tool for operation on different zones of the lens, the said spindles having independent actuating means including pulleys on the said spindles, and one of said 80 spindles being shorter than the other and terminating below the pulley of the longer 85 spindle.

2. A machine for grinding multifocal lenses comprising two oscillatory spindle 90 supports, rotary spindles carried by said supports and provided each with its own grinding tool for operation on different zones of the lens, the said spindles having independent actuating means including pulleys on the said spindles, one of said spindles being shorter than the other and terminating below the pulley of the longer 95 spindle, and independently driven variable throw crank connections for oscillating said 100 spindle supports substantially as described.

3. A machine for grinding multifocal lenses, comprising two oscillatory spindle supports, rotary spindles carried by said supports and provided each with its own 105 grinding tool for operating on different zones of the lens, the said spindles having independent actuating means associated with the spindles, one of said spindles being shorter than the other and terminating below the actuating means for the longer 110 spindle.

In testimony whereof I affix my signature in presence of two witnesses.

CHARLES A. HOFFMAN.
